UNITED STATES PATENT OFFICE.

ARTHUR KARR, OF YAKIMA, WASHINGTON.

LIGHTING TORCH.

Application filed May 10, 1924. Serial No. 712,325.

To all whom it may concern:

Be it known that I, ARTHUR KARR, a citizen of the United States, residing at Yakima, in the county of Yakima and State 5 of Washington, have invented certain new and useful Improvements in Lighting Torches; and I do hereby declare the following to be a full, clear, and exact description of the invention, such as will enable 10 others skilled in the art to which it appertains to make and use the same.

This invention relates to a lighting torch primarily designed to light briquette-burning orchard heaters from the top rather than 15 from the side.

One prime object is to provide a construction wherein but a predetermined quantity of fuel will be discharged incidental to each 20 tilting of the can and in which a lighting means is carried by the can in order to ignite such fuel.

Another object is to provide a novel construction to carry out the aforesaid object particularly in which the danger of the 25 flame reaching the interior of the can or source of the fuel will be overcome.

Additional objects and advantages will become apparent from a consideration of the description following taken in connection 30 with accompanying drawings illustrating an operative embodiment.

In said drawings:—

Figure 1 is a view of the invention in side elevation;

Figure 2 is a substantially central vertical sectional view of the invention, showing the same in fuel-discharging position,

Figure 3 is an elevation taken at a right angle to Figure 1, and

Figure 4 is a cross sectional view taken on the line 4—4 of Figure 2.

Like reference characters designate like or similar parts in the different views.

In reducing the invention to practice, a 45 can body or receptacle, usually of metal of any appropriate size or shape is provided as at 10, having a suitable pivoted bail 11 by which the device is carried when not in use and also provided with a handle as at 12 by 50 which the device is adapted to be held when in use. This handle is preferably of a construction whereby it may be made from a single sheet of metal having its main or grip portion cylindrical and end portions 13 55 extending therefrom and fastened to the can or receptacle. The receptacle also has a fill-

ing opening as at 14 normally covered by a screw cap 15, and further has a curved vent pipe as at 16 having its opposite ends soldered to the top of the can and top of handle 12, respectively. 16^a is the vent opening and it is preferably covered by gauze 16^b. The location of this vent avoids splashing out of the contents of the can.

The receptacle or body 10 has a pouring spout 17, of the same diameter as pipe 16, which interiorly of the can extends the full length thereof and is arranged radially of the bottom as at 18, being open and terminating short of and relatively close to the 70 side wall of the can as at 19. The spout 17 also extends a considerable distance exteriorly of the receptacle 10 and preferably has a curved discharge nozzle 20, provided with a screw cap 20^a removably holding a gauze 75 disk 20^b in the line of pouring.

Rising from the top of the can is a wick tube or spout 21 which is preferably soldered as at 22 to the tube 17 to reinforce and rigidify both of the tubes. Tube 21 rises 80 above the tube 20 and carries a wick 23 removably therein.

It will be understood that gauze disk 20^b prevents flame entering the can through tube 17, gauze shield 16^b through vent pipe 16, 85 and to prevent it entering through tube 21 copper or wire gauze 24 is soldered to the can and covers the inlet to tube 21, and the wick 23 preferably has copper or brass gauze 25 wrapped around the same and together with it is removably wedged in the outlet end of tube 21.

In using the device, wick 23 is saturated with liquid fuel and the body or can 10 is filled with such fuel which for instance may 95 be made up of equal parts of kerosene and gasoline, although either of these fuels may be used or any other. When the briquette or fuel of the orchard heater or otherwise is to be ignited, the operator having one hand 100 grasping the handle 12, tilts the article so that the tube 18 will be vertical with the end 19 uppermost and the quantity of fuel contained in it will flow through the spout 17 onto the briquette or the like. It will be 105 noted that the quantity of fuel discharged is thus premeasured, since other fuel cannot enter the spout 17 until the portion 18 is again placed in a horizontal position. When 110 the quantity of fuel is thus dispensed, the can may be tilted more so that the pressure of the fuel within the same will cause drops

thereof to penetrate the wick 23, and drop in ignited condition onto the dispensed fuel and thus ignite the same. Due to the frequent tilting and operation of the device, 5 the wick 23 will absorb sufficient fuel to keep it ignited after the initial ignition thereof.

Changes may be resorted to provided they fall within the spirit and scope of the invention.

10 I claim as my invention:—

A device of the class described having a container body, a pouring spout extending from the body, said spout being located partly interiorly and partly exteriorly of the 15 body and extending through the top of the latter, said spout at its base having a radial

inlet portion located on the bottom of the body and extending more than half way across the bottom and terminating relatively close to the adjacent side wall of the body 20 to avoid use of a valve, said portion being interiorly unobstructed, a wick tube extending from the top of the body to a point beyond the spout, said tube being relatively close to and connected to the spout, said 25 spout at its outer end being deflected away from the tube to form a nozzle, a securing element on said nozzle, and a foraminous safety means covering said nozzle and fastened by said securing element. 30

In testimony whereof I affix my signature.

ARTHUR KARR.
